UNITED STATES PATENT OFFICE.

IRA J. HESS, OF NELSON, KANSAS.

ROUNDABOUT.

No. 831,161.

Specification of Letters Patent.

Patented Sept. 18, 1906.

Application filed May 27, 1905. Serial No. 262,647.

To all whom it may concern:

Be it known that I, IRA J. HESS, a citizen of the United States, residing at Nelson, in the county of Crawford and State of Kansas, have invented certain new and useful Improvements in Roundabouts; and I do hereby declare the following to be a full, clear, and exact description of the invention, such as will enable others skilled in the art to which it appertains to make and use the same.

My invention relates to new and useful improvements in the class of roundabouts, and particularly to those adapted to be operated by the persons riding thereon.

The special object of my said invention is to so construct a device of the class described that the rocking motion imparted to the figures mounted thereon by the riders will transmit motion to the traveling wheels upon which the device is mounted.

In order that my invention may be thoroughly understood, I have illustrated the same in the accompanying drawings, and a full and exact description thereof is contained in the annexed specification.

In the accompanying drawings, Figure 1 is an elevation of my improved device. Fig. 2 is a top plan view thereof. Fig. 3 is a vertical section through the same. Fig. 4 is an enlarged detail view of a portion thereof. Fig. 5 is an enlarged detail view of a modification.

In the several views like letters of reference designate similar parts of my improved device.

A in the drawings designates a vertical post provided with a suitable base *a*, the upper end of said post being provided with a circular portion *a'* of smaller diameter than the lower portion.

B is a collar provided with a circular opening *b*, adapted to fit onto the spindle *a'* and rest upon the top of the enlarged portion of the post A. B is provided with the outwardly-extending flanges *b' b''*, between which

are secured by any suitable means the ends of radially-extending arms C C, forming the revolving frame, said arms C C being provided at their outer ends with the spindle portions *c c*, preferably of smaller diameter than the remainder thereof.

D D are brace-bars extending from the outer ends of the arms C C to a plate E, revolvably mounted on the end of the post A. F F are arms secured by any suitable means to said radially-extending arms C C and are provided with the axle portions *f f*, extending

directly under and parallel to the spindles *c c*. G G are wheels mounted on said axles *ff* and are adapted to bear upon and travel around the circular track H. J J designate the seats, which may comprise any form of figure, as a horse, chair, or the like, said seats or figures being mounted on the spindles *c c* to allow a rocking motion to be imparted to the same and being retained on said spindles by any suitable means, as the nuts *j j*. K K are links pivoted at one end at *k k* to the seats or figures J J at a suitable distance from the point of pivoting of same, the other ends of said links being provided with eyes *k' k'*, adapted to fit onto pins *g g*, located eccentrically on said wheels G G.

In the modification illustrated in Fig. 5 I employ a ratchet construction instead of the eccentric construction above described. Thus instead of connecting the lower ends of the links *k k* directly with the wheels G G, I pivot them at *k' k'* to short links L L, which are preferably pivoted to the axles *f f*. M M are ratchet-wheels concentrically mounted on the wheels G G. N N are pawls pivoted to the links L L and constructed to engage the said ratchets only upon the upward movement of the links K K. With this construction it is necessary to provide means for checking the movement of the seats, and to accomplish this object I provide the forwardly and rearwardly extending arms O and P, respectively, which are preferably rigidly secured to the spindles *c c*. Q Q are coiled springs interposed between the seat and the ends of the arms O and P to cushion the movement of the seats. R R are rods secured to the seat and extending through said springs and arms to prevent said springs from being displaced.

From the foregoing description the operation of my device is obvious and merely necessitates the rocking of the seats or figures by the riders to operate the links, which in turn revolve the wheels which set the whole device into operation.

Although I have shown my improved method of propulsion as applied to roundabouts, I do not wish to limit myself to such construction, as it may equally well be applied to go-carts, invalid-chairs, wheeled hobby-horses, and the like.

What I claim, and desire to secure by Letters Patent, is—

1. In a device of the class described, the combination with an upright post, of a frame comprising radially-extending arms revolu-

bly mounted thereon, seats mounted on the free ends of said arms to rock thereon, wheels revolubly mounted on axles connected with said arms, and connections between said seats and wheels whereby said wheels may be rotated, substantially as described.

2. In a device of the class described, the combination with an upright post, of a frame comprising radially-extending arms revolubly mounted thereon, seats mounted on the free ends of said arms to rock thereon, a cir-

cular track for said wheels and connections between said seats and wheels whereby said wheels may be rotated by rocking said seats, substantially as described.

15 In testimony whereof I affix my signature in the presence of two witnesses.

IRA J. HESS.
